UNITED STATES PATENT OFFICE.

JOHN J. NEVILLS, OF SACRAMENTO, CALIFORNIA, ASSIGNOR TO LIBBY, MCNEILL & LIBBY, OF CHICAGO, ILLINOIS, A CORPORATION OF MAINE.

FRUIT GRADER.

Application filed July 12, 1924. Serial No. 725,540.

The present invention relates to fruit graders.

The present invention will be illustrated and described particularly with reference to an apparatus for grading peaches, said apparatus having proven particularly useful for this purpose. It will be understood as the description proceeds, however, that the invention is of broader application.

10 An object of the present invention is to provide a grader for peaches or other articles which will expeditiously grade said articles according to size and which will occupy a minimum of space.

15 A further object is to provide a grader which will involve a minimum of clogging by the articles being graded and which will result in a minimum of bruising of said articles.

20 A further object is to provide a grader which is sturdy in construction and which is little liable to get out of order.

25 A further object is to provide a grader which is positive in its action and efficient in operation.

Further objects will appear as the description proceeds.

Referring to the drawings—

Figure 1 is a top plan view of a grader embodying the principles of the present invention;

Figure 2 is a view in side elevation of the structure shown in Figure 1;

Figure 3 is a view in end elevation of the structure shown in Figure 1;

Figure 4 is a sectional view taken along the plane indicated by the arrows 4—4 of Figure 2;

Figure 5 is a top plan view with parts removed to show the distributing chutes by means of which the graded articles are delivered from the machine; and

Figure 6 is a fragmentary sectional view taken along the plane indicated by the arrows 6—6 of Figure 5.

The numeral 10 indicates a cylinder comprising a plurality of longitudinally disposed screens of different mesh, said screens being supported in substantially cylindrical contour by means of the members 11—11. It will be noted from an inspection of Figure 4 that the member 10 is illustrated in polygonal form. Mounted symmetrically with the cylinder 10 is the outer cylinder 12, said outer cylinder being supported in spaced

relation relative to cylinder 10 by means of the members 13—13 (Figure 4). It will be noted that the member 12 is also indicated in polygonal form. It will be understood that when the term "cylinder" is applied to the members 10 and 12 in this specification, said term is to be broadly considered, in order that it may cover not only a true cylinder but an approximation thereof.

The cylinder 10 and the enclosing cylinder 12 will be mounted for rotation, part of the bearings necessary for said rotation being omitted for the reason that a disclosure of same is not considered necessary for an understanding of the present invention. Figures 1 and 3, however, illustrate a cylindrical band 13^a encircling the cylinder 10, which band rides upon the idler rollers 13'—13'. One end of the cylinder 10 may be provided with the gear 14, which gear 14 is driven by the pinion 14' (Figure 3). Turning movement is communicated to the pinion 14' by means of the bevel gears 15 and 16, which may have power transmitted to them by means of the shaft 17 and the pulley 18.

The cylinders 10 and 12 are mounted upon a framework 19 in an inclined position, that end of the cylinder 10 which is enclosed by the cylinder 12 being uppermost. The angular position of the cylinders 10 and 12 is illustrated in Figure 2.

The cylinders 10 and 12 include a plurality of screens of different mesh. Figure 1 shows part of cylinder 12 broken away to show the underlying screen of cylinder 10, said screen of cylinder 10 being marked "Mesh A". Communication to the left hand end of cylinder 10, as the parts are viewed in Figure 1, is had through the left hand end of said cylinder 10, a conical member 20 being provided for the reception of the articles to be graded. Articles which are small enough to pass through the screen marked "Mesh A" will pass into the outer cylinder 12.

Outer cylinder 12 is made up of two screens, arranged longitudinally of cylinder 12, which screens are indicated on the drawing as "Mesh B" and "Mesh C". Mesh "B" and Mesh "C" will both be smaller than Mesh "A", and Mesh "B" will be smaller than Mesh "C". Articles of the smallest size introduced into the machine will pass through the screen marked "Mesh B".

Articles of sufficiently large size to pass over screen marked "Mesh B" but of sufficiently small size to pass through the screen marked "Mesh C" will pass through said screen 5 marked "Mesh C". Articles of a size too large to pass through the screen marked "Mesh C" will pass out at the right hand end of cylinder 12. The means for carrying the graded articles away from the machine 10 will be referred to hereinafter.

The screen marked "Mesh A" of cylinder 10 extends from the left hand end of said cylinder 10 to a region indicated by the letters M—M (Figure 1). The section of cylinder 15 lying to the right of the line M—M and extending to the line N—N may be imperforate. Said imperforate section is indicated by the numeral 21 (Figure 1). Articles introduced into cylinder 10 which are of 20 too large a size to pass through the screen marked "Mesh A" will pass along the imperforate member 21. As the parts are indicated in the drawing, the right hand end of the imperforate section 21 is beyond the open 25 end of cylinder 12.

Arranged to the right of the plane marked by the line N—N are three screens, marked, respectively, "Mesh D", "Mesh E" and "Mesh F". Of the three screens referred to, 30 the one immediately to the right of the imperforate member 21, that is, the screen marked "Mesh D", will have the smallest mesh, that marked "Mesh E" will have the next larger, and that marked "Mesh F" will 35 have a still larger mesh. Articles of too large a size to pass through the screen marked "Mesh F" will pass out of the right hand end of cylinder 10.

Arranged under the cylinders 10 and 12 40 are collecting means for the articles graded by said cylinders 10 and 12. Under the cylinder 12 is the chute 22. A baffle 23 is mounted substantially in the plane marked by the line M—M, which plane is the right 45 hand boundary of the screen marked "Mesh B". Said baffle directs articles from chute 22 to a region laterally of the grader. To the right of the baffle 23 is the chute 24, which is bounded on the right by the baffle 24', lying in the plane of the right hand end 50 of cylinder 12. Mounted to the right of the baffle 24' is the chute 25 for carrying off articles which have passed into cylinder 12 from cylinder 10 but which are of too large 55 a size to pass through either screen marked "Mesh B" or screen marked "Mesh C". Articles passing from the right hand end of cylinder 12 are directed from chute 25 by means of the baffle 26. Arranged to the 60 right of the baffle 26 are the three chutes 27, 28 and 29, arranged below screens marked "Mesh D", "Mesh E", and "Mesh F", respectively, said chutes being bounded at their right hand extremities by the 65 baffles 30, 31 and 32, respectively. Said

chutes 27, 28 and 29 may be similar to chute 25 in conformation and have the function of directing graded articles away from the machine.

Arranged longitudinally of the machine is 70 the belt 33, which should be positively driven, said belt 33 being located in a trough 34. Said belt 33 will pass through slots in the various baffles referred to, whereby the movement of said belt will not be interrupted. 75 Graded articles, however, which have passed from the various screens on to said moving belt will be carried along with said belt until said graded articles are caused to move down the various chutes by reason of 80 the engagement of said articles with the baffles bounding said chutes. It will be noted from an inspection of Figure 2 that the plane of the upper side of the belt 33 is 85 higher at the region adjacent to the right hand end of cylinder 10 than in the region adjacent to the cylinder 12, the difference in height at the two regions being accomplished by the idler pulleys 35—35. By 90 reason of this construction the distance 95 which the graded articles are required to travel before reaching the belt 33 is reduced to a minimum.

In order to recapitulate the above description, the operation of the machine will be 95 described with reference to certain sizes of peaches. Peaches may be introduced into the open end of conical member 20 at the left hand end of the machine as the parts are viewed in Figures 1, 2 and 5. According to 100 a construction which is in actual use, the first screen, that is—screen marked "Mesh A", which said peaches will encounter in cylinder 10 will permit peaches of $2\frac{1}{16}$ inch diameter or less to pass through to cylinder 12. The 105 first screen of cylinder 12 which said peaches encounter, that is—screen marked "Mesh B", has such a mesh that peaches of $1\frac{3}{4}$ inch diameter or less will pass through into the chute 22 to be delivered at the side of the machine. The second screen encountered in cylinder 12, that is—screen marked "Mesh C", has such a mesh that peaches which are of too 110 large a diameter to pass through screen "Mesh B" and which are of a diameter of $1\frac{2}{9}$ inch or less will pass through said screen marked "Mesh C". Peaches of a diameter between $1\frac{3}{2}$ and $2\frac{1}{16}$ inches pass out through the outer end of cylinder 12. Peaches passing through screen marked "Mesh C" will 115 pass out through chute 24 to the side of the machine, and peaches which pass out of the right hand end of cylinder 12 will be delivered by chute 25 to the side of the machine. 120

Peaches which are too large to pass through the screen of cylinder 10 marked "Mesh A" will pass over the imperforate portion 21 and will encounter in succession the screens marked "Mesh D", "Mesh E" and 130

"Mesh F", respectively. Continuing the example, screen marked "Mesh D" may permit peaches of $2\frac{1}{8}$ inches diameter to pass, screen marked "Mesh E" may permit peaches of a diameter of $2\frac{5}{16}$ inches to pass, and screen marked "Mesh F" may permit peaches of a diameter of $2\frac{1}{2}$ inches to pass. Peaches larger than $2\frac{1}{2}$ inches in diameter will pass out of the right hand end of cylinder 10.

It will be understood that the peaches entering chutes 22, 24, 27, 28 and 29 will drop onto the moving belt 33 and will be constrained by the corresponding baffles 23, 24, 15 30, 31 and 32 to pass to the side of the machine. Peaches which have passed out of the right hand end of cylinder 12 will be delivered to the side of the machine by chute 25. Peaches of more than $2\frac{1}{2}$ inches diameter which are delivered at the right hand end of cylinder 10 may be collected in any preferred way, not illustrated.

The practical advantages of the structure above described will be better understood after a short discussion of the commercial problems encountered in the handling of peaches. The present invention is particularly applicable to the sorting of peaches for canning purposes. Commercially, peaches which may be canned in halves have a decided advantage over peaches which must be sliced for canning. On the other hand, peaches of small size have less commercial value per unit of weight and are regarded as seconds. The choice peaches for canning purposes, therefore, are intermediate in size between a small or medium size peach and a large peach. In the ordinary graders as heretofore used, the small and medium size peaches have been sorted out first and have therefore been subjected to the least handling mechanically. Peaches of the choice sizes for canning purposes have necessarily been handled in the grading machines to a very considerable amount. Larger size peaches, which, though not adapted for canning in halves, are nevertheless very valuable commercially in the peach canning industry, get the greatest amount of handling, and therefore are most subject to injuries. The present invention as above described has the important mechanical advantage that the most important sizes, considered commercially, are given a minimum of handling in the grading operation. Referring to the example above recited, peaches $1\frac{3}{4}$ inches in diameter or less are too small to be canned as first-grade choice peaches for canning purposes. Peaches of larger size, up to $2\frac{1}{16}$ inches in diameter, are very choice. According to the present invention, said very choice peaches ranging from $1\frac{3}{4}$ inches up to $2\frac{1}{16}$ inches in diameter are separated almost immediately from the peaches of a

larger diameter than $2\frac{1}{16}$ inches. Inasmuch as the greatest danger of injury to the peaches is due to their tumbling against one another, the almost immediate separation of peaches of less than $2\frac{1}{16}$ inches in diameter from those of larger size has a very decided practical advantage. Inasmuch as the peaches of $1\frac{3}{4}$ inches and less diameter are graded out in the first stage in cylinder 12, the exposure to bruising effects of the choice peaches, that is—those between $1\frac{3}{2}$ inches and $2\frac{1}{16}$ inches, is decidedly minimized.

Decidedly practical advantages accrue, moreover, from the polygonal form of the members 10 and 12, which for purposes of convenience have been referred to in this specification as cylinders. In the sorting of peaches for canning purposes, said peaches are ordinarily halved and are sorted in said halved condition. Were the cylinders 10 and 12 to be of true mathematical cylindrical form, the halved peaches would tend to slide, and therefore would not be carried by the revolving members 10 and 12 to the height accomplished with the polygonal members 10 and 12. Due to the polygonal form, the halved peaches have much better contact with the inner walls of said members 10 and 12, and are carried to considerably greater height before tumbling back toward the lower regions of said members 10 and 12. Sorting is thereby greatly expedited by the polygonal form illustrated.

Though an example has been taken from actual practice in the above description indicating certain sizes of peaches, it is to be understood that said example is to be considered in an illustrative way and not in a limiting way. The invention is subject to many modifications. It is intended to cover all such modifications that fall within the scope of the appended claims.

What is claimed is:

1. In a grader, in combination, a pair of concentric members of polygonal contour, one of which envelops the other throughout a portion of the length of said other adjacent to the inlet end thereof, said concentric members of polygonal contour comprising screen members of different mesh, the mesh of the screens of said inner concentric member being progressively greater from the inlet end thereof to the outlet end thereof, the mesh of the screens of the outer concentric member being less than the smallest mesh of the screens of the inner concentric member and increasing progressively from the inlet end to the outlet end thereof, whereby members of intermediate sizes are sorted out relatively soon after insertion into said inner concentric member.

2. A grading machine particularly adapted for the grading of fruit of approximately hemispherical form comprising, in combination, a pair of concentric members of po-

lygonal contour, one of which envelops the other throughout a portion of the length of said other adjacent to the inlet end thereof, said concentric members comprising screen members of different mesh, the screen members of the outer concentric member being progressively greater from the inlet end to the outlet end thereof, the largest mesh of said outer concentric member being less than the smallest mesh of the inner of said concentric members, the screen members of said inner concentric member increasing progressively in mesh from the inlet to the outlet end thereof, whereby articles of fruit of a plurality of intermediate sizes are sorted out from each other and from the remainder of the fruit relatively soon after insertion into said inner concentric member.

3. In a grader, in combination, a pair of

concentric cylinders, one of which envelops the other throughout a portion of the length of said other adjacent to the inlet end thereof, said cylinders comprising screen members of different mesh, the mesh of the screens of said inner cylinder being progressively greater from the inlet end thereof to the outlet end thereof, the mesh of the screens of the outer cylinder being less than the smallest mesh of the screens of the inner cylinder and increasing progressively from the inlet end to the outlet end thereof, whereby members of intermediate sizes are sorted out relatively soon after insertion into said inner cylinder.

Signed at Sacramento, California, this 19th day of May, 1924.

JOHN J. NEVILLS.
